COMBINATION UNDERGARMENT

Sallee Hoenig, New York, N. Y.

Application January 15, 1947, Serial No. 722,209

9 Claims. (Cl. 2—30)

1

This invention relates to improvements in combination garments, which has for its object to provide a light and form-fitting garment adapted to snugly follow and mold every delicate curve of the feminine figure while supporting and molding the bust, diaphragm, abdomen and hips.

An object of my invention is to provide a garment of the character described which will give a firm support to the busts and at the same time will be capable of encircling the waist and torso portion thereof, allowing freedom of movement in the brassière portion, and at the same time giving grace and flexibility to the waist and torso portions of the garment.

Another object is to provide in a combination garment of the character described, bust pocket members incorporated therein and so constructed and arranged as to afford flexibility and shift to hold the wearer's bust firmly, sufficient and proper, during lateral twisting of the wearer's body.

Yet another object of my invention is to provide a combination garment of the character described formed with bust pocket members incorporated therein and so constructed as to afford flexibility and room for the expansion of the pockets during periods when the bust of the wearer assumes larger than normal proportions.

Still another object of my invention is to provide a combination garment of the character described, wherein the brassière pockets are separable from the girdle portion member thereof.

A further object of my invention is to provide an improved combination garment of the character described, the lower and upper body portions whereof are easily adjustable to the waist length of the wearer and the skirt portion whereof shall have yieldable elasticity for the expansion and contractions thereof in any posture of the wearer.

A yet further object of the invention is to provide a combination garment of the character described, in which the pull on the garter portion of the garment shall cause no strain on the upper portion of the garment, whereby the vertical support will permit the greatest possible lateral pull, twisting movement without discomfort.

Still a further object of my invention is to provide a combination garment of the character described, constructed with ventilation openings between the brassière pockets and the girdle portion so as to firmly support the busts and permit of the greatest possible lateral twisting or shifting movement.

Another object of my invention is to provide

2 a combination garment with releasably attachable back members at the upper end of the garment, split from the body of the garment, and so constructed as to easily fasten and unfasten, while at the same time greatly minimizing the possibility of its unfastening of itself.

Yet another object of my invention is to provide an improved durable combination garment which shall be inexpensive to manufacture, wherein the flexible coacting back members are adapted to permit yielding effects in the garment to accommodate the movements of the body, which shall be attractive in appearance and practical and efficient to a high degree in use.

Yet another object of my invention is to provide a combination garment of the character described wherein the brassière member portion is provided with detachable shoulder straps and the upper portion of said brassière member is so constructed as to have insertible and removable stays, forming thereby a support for said brassière member without the use of shoulder straps.

These and other objects of my invention are made more obvious in connection with the accompanying description and drawing in which:

Fig. 1 is a front perspective view showing the garment embodying the invention in use.

Fig. 2 is a rear perspective view of the garment shown in Fig. 1.

Fig. 3 is a cross-sectional view taken on line 3—3 of Fig. 2.

Fig. 4 is a cross-sectional view taken on line 4—4 of Fig. 1.

Fig. 5 is a fragmentary perspective view of the upper portion of the garment, illustrating a modified construction.

Fig. 6 is a cross-sectional view taken on line 6—6 of Fig. 5.

Referring now in detail to the drawing, 10 designates a garment embodying the invention here shown as a foundation garment or a combination brassière and girdle.

Said garment 10 comprises a pair of front, 45 symmetrical front sections, 11 attached together by a front center seam or tape 12. Sections 11 extend from the lower end of the garment to its upper edge. The upper ends, 11a of the sections 11 are inclined upwardly and inwardly toward an apex 13 located between the breast or bust pockets 14. Said sections 11 may be made of cloth cut on the bias if desired to give greater elasticity to the garment.

Attached to sections 11 are a pair of symmetrical front sections 16 which may also be made

of cloth cut on the bias. Between sections 11 and 16 are the seams or tapes 17.

Sections 16 extend from the lower edge of the garment to edges 18 which are continuations of edges 11a of sections 11. Sections 11 and 16 vary in width so as to give shape to the garment and to conform to the waist and hips of the wearer.

Between sections 11 at their lower ends is received a triangular elastic gusset 20.

Stitched to front sections 16, about seams 21, are the side sections 22 made of elastic cloth such as two way stretch textile material. Sections 22 extend to the lower end of the garment. Said sections 22 extend up to a point 23 below the upper end of the garment. Sections 22 are interconnected about taped seams 22a by a back section 24 which may be made of cloth cut on the bias or straight. The lower edge of back section 24 is at the lower end of the garment. Said back section terminates at its upper end in an edge 26. Said section is split down the middle from its upper edge down to a point near the waistline, and the split edges are provided with slide actuated fasteners 29.

Stitched to sections 22 by V-shaped seams 30 located below the upper ends 23 of said sections, are sections 31 of cloth overlying and extending above said sections 22 to downwardly and rearwardly inclined upper edges 33. Stitched to sections 31 about taped seams 22b, which are extensions of taped seams 22a, are substantially triangular sections 35. Said sections 35 are seamed to the upper end of back section 24 by seams 36 which extend from seams 22a inwardly but terminate short of the central split in said back section. Such construction provides straps 37 at the inner ends of sections 35. Said straps 37 are located at the upper end of the back of the garment adjacent the brassière portion of the garment. Said straps 37 may be releasably fastened by hook and eye fasteners 38, or buttons and button holes or by any other quickly detachable fastening means. In Fig. 2, the fasteners 38 are shown opened or detached. The straps, being split from the back 24, permit stretching of the garment, and allow free bending or twisting of the body of the wearer.

I have discovered that by leaving the upper portion of the back members free and not secured to the skirt member of the garment, I thereby obtain freedom of movement, the back portion adjusting itself to accommodate the body shifts and yielding to any movement of the body of the wearer, without strain on the remaining portions of the garment.

I have also discovered that this free upper back portion holds the garment in closed position, is simple for unfastening, since it is flexible. It moreover prevents the riding of the zipper closure, sometimes caused by motion of the body, since it serves as a separate and independent closure means.

This free portion also permits flexibility on the remaining portions of the garment, obviating thereby strain on the rear portion of the garment due to lateral twist or pull, and substantially supports the upper portion or bust portion of the garment.

At the upper ends of sections 11 are angularly inclined darts 40 extending to the upper edges of said sections, for the purpose of shaping the garment, for additional room for support of the breasts in addition to the support

provided by the breast pocket members adjacent thereto.

The breast pockets 14 may each have a lace outer portion 41, and an inner cloth reinforcing portion 42 at its inner side, and located at the lower side of the pocket. Portion 42 may be stitched to portion 41 by lines of stitching 43. The lower edge 45 of the pocket is spaced from the upper edges, partly of sections 11, 16, producing a crescent shaped opening 50. At opposite sides of opening 50, each pocket is attached to sections 11 and 22 by slide actuated fasteners 53, 54, respectively. Said fasteners are of the type which permits entire separation of the pockets from the remainder of the garment. If desired the sides of the pockets may be stitched to sections 11, 22 at 53, 54, respectively, instead of being detachably attached thereto by slide fasteners or other quickly detachable means.

20 Breast pockets 14 may be connected to the back sections 31 by shoulder straps 60 if desired. When the breast pockets 14 are detached, the shoulder straps can be cut from said pockets. Thus the garment may be worn without the 25 breast pockets.

Furthermore, the provision of openings 50 permits ease of movement of the body and allows for expansion of the busts.

I have discovered that this opening 50 gives 30 the bust of the figure substantial support, the pull on the garment not affecting the cup portions 14. Moreover, this opening is a means of ventilation.

35 Regardless of the posture of the wearer, or the strain on the garment, or the pull of the hose supporter, the cups retain the busts while the resilience of the cups in combination with the darted adjacent thereto portion of the garment, give additional room for expansion of the cups 40 and accommodate room for the busts whenever the busts fill up and enlarge.

Moreover, I have discovered that this opening 45 is essentially of advantage to the wearer's comfort since no artificial pressure is exerted thereby upon the bust, such as might result in certain organic indispositions to which this delicate portion of the body is susceptible.

There is a decided advantage in making the 50 pockets 14 separable since the separable garment is easier to clean or wash. At the same time, the member portions may be used separately or jointly, that is, the girdle member without the brassière, or both brassière and girdle members together as a unit.

55 In Figs. 5 and 6, there is shown a modified construction. Garment 10a illustrated in Figs. 5 and 6 is the same as the garment shown in Fig. 1 except that the shoulder straps are replaced by stiffeners or stays 71 in pockets 72 stitched to the bust pockets 14 and radiating from the apex of each pocket.

60 I may make the shoulder straps which are illustrated in Fig. 1 detachable and securable to the bust pockets by means of buttons, or hook and eye, or snap fastener, or any other means 65 of securing the said straps to the bust pockets of said combination garment.

I have discovered that by stitching these pockets 72 to the reverse or so-called left side of the 70 bust pocket, I thereby provide room for the insertion and removal of any type of rigid yet flexible stay, which will at the option of the wearer act as a support of the garment, without recourse to shoulder straps.

75 While I have tried to describe the invention in

its detail, such slight modifications thereof as embody in principle the invention are, of course, understood to be within the scope of the present invention.

Having described my invention, what I claim is:

1. A combination girdle and brassière garment, comprising a body extending from below the hips of the wearer to just below the breasts of the wearer at the front of the garment, and to above the waistline of the wearer at the back of the garment, and a pair of breast pockets separate from one another, each breast pocket having a curved lower edge having upwardly and outwardly inclined outer portions, and said body being formed at its upper end with a pair of curved edges each having upwardly and outwardly inclined edge portions complementary to the lower upwardly and outwardly inclined edge portions of each pocket, and means for detachably attaching each pocket to said body portion at said upwardly and downwardly inclined complementary edge portions of said pocket and body, the means for detachably attaching each pocket to the body being spaced from one another and each pocket being separable from the body by detaching the means which detachably attaches each pocket to the body.

2. A combination girdle and brassière garment, comprising a body extending from below the hips of the wearer to just below the breasts of the wearer at the front of the garment, and to above the waistline of the wearer at the back of the garment, and a pair of breast pockets separate from one another, each breast pocket having a curved lower edge having upwardly and outwardly inclined outer portions, said body being formed at its upper end with a pair of curved edges each having upwardly and outwardly inclined edge portions complementary to the lower upwardly and outwardly inclined edge portions of each pocket, means for detachably attaching each pocket to said body portion at said upwardly and outwardly inclined complementary edge portions of said pocket and body, the means for detachably attaching each pocket to the body being spaced from one another and each pocket being separable from the body by detaching the means which detachably attaches each pocket to the body, said body being formed at the back with an upper edge portion and with a slit extending down from said last mentioned upper edge portion, means for detachably attaching opposite sides of said slit together, and said garment further being formed at the back and above said last mentioned upper edge portion with a pair of strap sections extending from the sides of the garment toward each other, and said sections being separated from the last mentioned upper edge portion, and means for detachably attaching together the meeting ends of said straps.

3. A combination girdle and brassière garment, comprising a body extending from below the hips of the wearer to above the waistline of the wearer and a pair of separate breast pockets, means for attaching spaced portions of the lower edge of each breast pocket to spaced portions of the upper edge of the body so that said breast pockets are individually detachable from said body and are separable from one another, the lower edge of each breast pocket and the upper edge of the body between the pair of spaced attaching means for said pocket being spaced from one another to form an opening between each breast pocket

and the body and between the spaced attaching means for said pocket.

4. A combination girdle and brassière garment, comprising a body extending from below the hips of the wearer to above the waistline of the wearer, and a pair of separate breast pockets, means for attaching spaced portions of the lower edge of each breast pocket to spaced portions of the front of the upper edge of the body so that said breast pockets are individually detachable from said body and are separable from one another, the lower edge of each breast pocket and the upper edge of the body between each pair of spaced attaching means for said pocket, being spaced from one another to form an opening between each breast pocket and the body and between the spaced attaching means for said pocket, said body at the back being formed with an upper edge and with strap sections extending toward each other and above said last mentioned upper edge and spaced therefrom, and means for detachably attaching together the inner ends of said strap sections.

5. A combination girdle and brassière foundation garment comprising a body portion having side sections and a back section connecting said side sections, and pair of separate breast pockets removably attached to said body portion, each breast pocket being attachable to said body by spaced fastener means leaving an opening between said spaced fastener means where the central portion of the lower edge of each breast pocket is unconnected to said body; said garment being provided with a pair of straps extending from said side sections and detachably attached to said breast pockets, respectively; said body being formed at the back thereof with an upper edge portion, a slit extending down from said upper edge portion and a slit extending horizontally in between said upper edge portions and said lower edge portion of said back portion of said garment, and fastening means for said downward-slit back portions of the garment aforesaid.

6. A combination girdle and brassière foundation garment comprising a body portion having front sections, and a pair of separate breast pockets each having edge portions at opposite ends of the lower edge thereof, means for removably attaching said edge portions to spaced edge portions of the upper edge of said front sections of said body portion, each breast pocket being unattached to said body between said spaced fastener means to form an opening, said body being provided with darts extending to said opening, said body at the back being formed with free upper end portions and a slit extending down below said free upper end back portions, and fastening means for said free upper end portions of said garment and also fastening means for said opposite sides of said extending downward slit portion of said back portion of said garment.

7. A combination girdle and brassière garment, comprising a body extending from below the hips of the wearer to just below the breasts of the wearer at the front of the garment, and to above the waistline of the wearer at the back of the garment; said body being formed at its front end with a pair of curved edges each formed with upwardly and outwardly inclined outer edge portions; and a pair of breast pockets separate from one another and separate from said body; each of said breast pockets having a curved lower edge of which its upwardly and outwardly inclined outer edge portions are complementary to the upwardly and outwardly inclined edge portions of

7
said body; means for attaching and detaching each pocket to said body at said upwardly and outwardly inclined edge portions of said curved edges of said pocket and body; said outwardly and upwardly attaching and detaching means being spaced apart and the space between said attaching and detaching means comprising a crescent shaped opening; said body being formed at back with a slit extending vertically down the middle from its upper edge portion, and having means for closing and opening the opposite sides of said slit.

8. The structure in accordance with claim 7, and said garment further being formed at above the upper edge portion of said back with a pair of strap sections, said strap sections having free ends, and means for attaching and detaching said free ends of said strap sections.

9. The structure as set forth in claim 8, and said breast pockets having shoulder straps de- 20

tachably connected thereto and the back of the garment aforesaid.
